UNITED STATES PATENT OFFICE.

FREDERICK FRENGLE, OF COTATI, CALIFORNIA.

ADJUSTABLE BROODER HOVER.

Application filed May 4, 1926. Serial No. 106,612.

This invention relates to adjustable brood-
er hovers of the type used in protecting
baby fowl.

In caring for baby chicks it has been the
5 practice for poultry raisers to provide an en-
closed room in which is located a conical
shaped hover having a stove or other heat
producing means positioned centrally there-
in. The baby chicks not having any natural
10 protection from the cold, gather under the
conical shaped hover which affords suitable
warmth and protection during the period
needed. As the chicks become older and can
move about, suitable roosting places should
15 be provided inside the room just beyond the
edges of the hover. Heretofore it has been
difficult to provide a room suitable in size
to accommodate sufficient places for roost-
ing purposes owing to the fact that the hover
20 usually fits inside the room with very little
space on the outside thereof, and as a con-
sequence the baby chicks could not be prop-
erly cared for. My present invention, com-
prising a hover adjustable in size, affords
25 a suitable means for permitting the space
located outside the hover to be increased con-
siderably, thereby permitting suitable roost-
ing places to be furnished for the baby
chicks.

30 An object of this invention is to provide
a brooder hover having adjustable means
thereon for increasing or decreasing its size.

Another object of this invention is to pro-
vide an adjustable brooder hover having
35 convenient means attachable thereon for in-
creasing its size.

Another object of this invention is to pro-
vide an adjustable brooder hover having
thereon a detachable means whereby its size
40 may be decreased.

In the accompanying drawings forming
a part of this application:

Fig. 1 is a side view of the hover embody-
ing my invention, the same being positioned
45 inside an enclosure and ready for use;

Fig. 2 is a bottom plan view of one of the
sections used to increase the size of a hover;

Fig. 3 is a top plan view of a hover em-
bodying my invention;

50 Fig. 4 is a sectional view taken on the line
4—4 of Fig. 3; and

Fig. 5 is a sectional view taken on the line
5—5 of Fig. 2.

Referring to the drawings, the numeral 1
55 illustrates a conical shaped top piece hav-
ing its ends joined together by rivets 2, and

provided centrally with an opening 3. Se-
cured to the underneath side of the top piece
1 by rivets 4 and extending above the upper
surface of the said top piece through suit-
able slots therein, are a number of hooks 5
which serve as means for suspending the top
piece and the parts secured thereto in a
suitable enclosure.

Located immediately beneath the outside
edge of the top piece and extending entire-
ly around the same is a band 6 which is
separated from the edge of the said top
piece and held in place thereon by a plural-
ity of downwardly extending members 7. 65
The downwardly extending members 7 are
secured to the top piece 1 at the outside edge
thereof by rivets 8, and to the band 6 by
rivets 9, thereby securely maintaining the
said band immediately beneath the outside 70
edge of the said top piece and in a separated
position therefrom.

In order to increase the breadth of the
conical shaped top piece 1, I have provided
a plurality of extension members 10, each 80
having an end piece 11 which is adapted to
be inserted between the top edge of the band
6 and the underneath surface of the edge of
the top piece 1 and between the downwardly
extending members 7. The outside edges 85
12 of the extension members 10, are bent
downwardly, and are provided at one side
with a downwardly bent edge 13 and at the
other side with an inwardly and down-
wardly bent part 14. Each of the extension 90
members 10, when the same is positioned at
the edge of the top piece 1, between the out-
side edge thereof and the band 6, contacts
with another of the said extension mem-
bers in such a manner that one of the bent 95
edges 13 lies adjacent the downwardly bent
part 14, with the inwardly disposed portion
of the said part 14 resting on the top sur-
face of one of the adjacent members 10. The
outside edges 12 of extension members 10 100
are each provided with a pair of suitable
holes through which the bolts 15 may ex-
tend to hold the said members 10 together
and in joined positions just beyond the out-
side edge of the top piece 1. The extension 105
members 10, when the same are joined to-
gether and are attached to the edge of the
top piece 1, afford a suitable means for in-
creasing the size of the said top piece.

In practice the top piece 1 with the ex-
tension members 10 attached thereon, is sus-
pended in a suitable enclosure or room 16,

by the cords or ropes 17, which are fastened to hooks 5 of the said top piece and extend through pulleys 18 to a counter balancing weight 19. The weight 19, through the cords 17, holds the top piece with its extension members in the desired position above the floor of the enclosure. Located beneath the top piece 1 is a suitable stove 20, and the pipe 21 extends from the stove through the opening 3 in the said top piece and through the ceiling of the enclosure. When it is necessary to increase the space within the enclosure 16, so as to provide suitable roosting places for the baby chicks, the extension members 10 are unfastened from the center piece 1, thereby decreasing the size of the hover and affording more space between it and the walls of the room.

It is evident that the improved hover herein shown and described can be constructed from any suitable material such as wood or sheet metal, and that it may be made to assume other shapes than that illustrated. I therefore do not desire to be limited to the exact shape or construction herein shown, but desire that my invention and the various forms it may assume, be included within the spirit of the appended claims.

Having described my invention, what I claim is:

1. An adjustable brooder hover comprising, a top piece, a plurality of joined extension members attachable to the edge of the

top piece, and a band secured to the top piece for maintaining the extension members at the edge of the top piece.

2. An adjustable brooder hover comprising a top piece, a plurality of joined extension members attachable to the edge of the top piece, means for maintaining the extension members in a joined position, and a band secured to the top piece for maintaining the extension members at the edge of the top piece.

3. An adjustable brooder hover comprising a top piece, an extension member attachable to the edge of the top piece, a band secured to the top piece for maintaining the said extension member in position at the edge of the top piece.

4. An adjustable brooder hover, comprising a conical shaped top piece having a plurality of joined extension members removably attached to its outside edge, and a band secured to the top piece whereby the said extension members are maintained in position on the top piece.

5. An adjustable brooder hover comprising a conical shaped top piece, a plurality of extension members removably attached to the edge of the top piece and extending beyond the edge of the top piece, means for joining the extension members together, and a band secured to the edge of the top piece for holding the extension members in position at the edge of the top piece.

FREDERICK FRENGLE.
